UNITED STATES PATENT OFFICE.

CHARLES W. DIKEMAN, OF RACINE, WISCONSIN.

MACHINE FOR MAKING RUGS, &c.

SPECIFICATION forming part of Letters Patent No. 320,339, dated June 16, 1885.

Application filed December 13, 1884. (No model.)

To all whom it may concern:

Be it known that I, CHARLES W. DIKEMAN, of Racine, in the county of Racine, and in the State of Wisconsin, have invented certain new and useful Improvements in Machines for Making Rugs, &c.; and I do hereby declare that the following is a full, clear, and exact description thereof.

My invention relates to the manufacture of carpets, rugs, &c., and will be fully described hereinafter.

In the drawings, Figure 1 is a side elevation of a machine embodying my invention. Fig. 2 is a front end view of the same. Fig. 3 is a detail illustrating the operation of my device. Fig. 4 shows the nature of the fabric made by the machine, and Fig. 5 is a detail.

A is a frame that may be clamped to the table of a sewing-machine, lathe, or any other machinery from whence it may get its power.

B is the driving-shaft, and C C' are eccentrics that are keyed onto the driving-shaft. Each of these eccentrics is encircled by a band, e, from which depends a swinging hanger, D, 25 that connects by a universal joint, d, with the rear end of a lever, D' or D''. These levers D' D'' are pivoted to the arm of the frame A by a bolt or stud, a', that passes through slots therein, and these levers may be adjusted and secured in adjustment on the pivot by any suitable means for changing the stitch. The front end of lever D'' is connected with a hub, E, by a link, D', and the arm E' of this hub slides in a slot, f, in the head F of the machine.

G is an upright bar that passes through the hub and is secured in adjustment therein by a set-screw, (not shown,) and on the lower end of the bar G is secured a looping-finger, g. This finger may be formed with a hollow head 35 to receive the lower end of the bar G, as shown in the drawings, or the bar may be enlarged and bored at its base and the head of the finger reduced and secured therein; but in either case a set-screw, g', will by preference be used 40 to secure them together. The lever D' is connected by precisely similar mechanism with another upright bar, H, the connection being made by a link, h, to the arm h' of a hub, H'; but on the lower end of bar H, I fix a needle, 45 K. The head of this needle may be constructed

with a bore to receive the bar H, or may be fitted into the bar, the needle and finger being alike in this respect.

That portion of the needle K that enters the fabric is flattened, and near its point it has an eye, k, to receive a strip of material that is to be looped into a backing of gunny bagging or any other fabric of loose texture. The lower portion of the finger g is tapered and curved so that the point, which is rather blunt, approaches very near the line of travel of the needle.

L is a hollow block or shoe that is secured to or forms part of a hinged platform, L', and while the hinge supports one edge of this platform the other is supported by a cam, l, of a shaft, M, that turns in a bearing, m, secured to the under side of the frame A, so that by turning the shaft M the cam can be made to drop the platform L' and its shoe out of the way in inserting or removing work.

N is the backing which, as before stated, may be of any loose-textured material, and N' is a reel that carries the material n to be looped into the backing for the formation of rugs, carpets, &c.

The operation of my device is as follows: The fly-wheel P is to be bolted to any convenient source of power, and the needle is to be threaded with the material n on the reel, 55 which may consist of yarn, or rags, or leather, in one continuous strip or piece. The backing N is placed over the shoe or block L, and the shaft B started, and as it revolves its eccentrics will, through the mechanism that connects them with the bars G and H, reciprocate them alternately, the result being that the material n will be carried through the backing N, and then, as the needle rises, the finger will catch the material n and hold it down 60 against the tendency of the needle to lift it, and at the same time the convexity in the finger will by wedging draw the backing slightly, so that a new surface will be presented to the needle on its downward stroke, and thus 65 the yarn or other material will be distributed in the backing, as shown in Figs. 3 and 4, after which the loops may be sheared off to form a kind of fulling for the wearing surface 70 of the rug or carpet. The lower end of fin- 75

ger is preferably notched that it may take firm hold upon the material *n* as it presses down upon it.

Having thus fully described my invention, 5 what I claim as new, and desire to secure by Letters Patent, is—

1. In a machine for making rugs, &c., the combination of a needle and looping-finger mounted on the ends of vertically-reciprocating bars, said bars being connected by levers to eccentrics keyed on the driving-shaft of the machine, whereby the said needle and finger are reciprocated alternately, substantially as set forth.
- 15 2. The driving-shaft and its eccentrics in combination with the needle and looping bars, the links, levers, and swinging hangers, substantially as described.
- 20 3. The combination of the needle and finger with the block *L* and platform *L'*, hinged to the base of the frame, and adapted to be lowered for the more ready insertion or removal of work, as set forth.
- 25 4. In a machine for making rugs, &c., the combination of the frame *A*, driving-shaft *B*, eccentrics *C C'*, keyed thereto, swinging hangers *D*, and slotted levers *D' D'*, pivoted to the arm of the frame and connected to the hangers *D* by universal joints at one end, and at their 30 other end connected to the upright bars of the

needle and looping-finger, substantially as set forth.

5. In a machine for making rugs, &c., the combination of the driving-shaft, its eccentrics and hangers, and levers *D' D'*, connected thereto, with the head *F*, having vertical slots in its front face, and arms *E'* and *H'*, passing through and moving in said slots, said arms being connected to the described levers by links *h* and *D'* outside of said head, and to vertical bars *G H* by hubs *E* and *H'* within said head, substantially as set forth.

6. In a machine for making rugs, &c., the combination of the alternately-reciprocating needle and finger with the block *L*, hinged 45 platform *L'*, bearing *m*, secured to the under side of the machine-frame, and shaft *M*, having cam *l* at one end adapted to support one edge of the hinged platform or to permit it to be lowered by turning said cam, substantially as set forth.

In testimony that I claim the foregoing I have hereunto set my hand, at Milwaukee, in the county of Milwaukee and State of Wisconsin, in the presence of two witnesses,

CHARLES W. DIKEMAN.

Witnesses:

S. S. STOUT,
H. G. UNDERWOOD.
